United States Patent Office

Des. 184,720
Patented Mar. 31, 1959

184,720

BOX FOR AN INK PAD OR THE LIKE

Jack F. Fleming, Summit, N.J., assignor to The Carter's Ink Company, Cambridge, Mass., a corporation of Massachusetts

Application November 30, 1956, Serial No. 44,011

Term of patent 14 years

(Cl. D58—12)

Fig. 1 is a plan view of the top of a box for an ink pad or the like embodying my new design;

Fig. 2 is a front elevation thereof;

Fig. 3 is a rear elevation thereof; and

Fig. 4 is an elevation of one end of the box, both ends being identical.

I claim:

The ornamental design for a box for an ink pad or the like, substantially as shown and described.
